CLAIM

The ornamental design for a dry shaver, as shown and described.

DESCRIPTION

FIG. 1 is a perspective view of a dryer shaver showing our new design with the cover element removed for clarity of illustration;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is a perspective view of the assembled article.

The undisclosed portions of the cover are plain and unornamented, and follow the configuration of the sides shown.
